UNITED STATES PATENT OFFICE

LILI JUST, OF NEW YORK, N. Y., ASSIGNOR TO THE E. V. D. COMPANY, INC., OF NEW YORK, N. Y., A CORPORATION OF DELAWARE

BATHING SUIT

Application filed November 21, 1932. Serial No. 643,687.

This invention relates to bathing suits of the one-piece style, and is concerned more particularly with a one-piece suit of novel construction which is of attractive appearance, affords the necessary protection to the wearer while giving the desired exposure of the back, and can be worn with complete comfort and without binding because of certain features of adjustment incorporated in it.

The new garment includes trunks, a shirt, and a top which covers the front of the body only and is provided with extensions over the shoulders and side extensions under the arms. At the back the trunks and shirt terminate at the waistline and the back of the wearer is fully exposed except for certain straps. There are two of these straps each connecting a shoulder extension to a side extension and thus defining arm holes which are preferably quite large. Another pair of straps are attached to the top of the rear part of the trunks to extend upward therefrom and, when the suit is put on, each of these straps is led up beneath one of the connecting straps and passed through an arm hole, the free ends of the two straps being then brought together at the middle of the back and tied. The pull of these straps on those which connect the extensions causes the front of the garment to be drawn and held closely about the body of the wearer and the straps attached to the trunks are sufficiently long so that they provide a considerable degree of adjustment in the tightness of the front of the suit.

The new garment includes various features of novelty in addition to those mentioned, which will be pointed out in the detailed description of the invention to follow.

For a better understanding of the invention, reference may be had to the accompanying drawing, in which

Fig. 1 is a view of the new garment in perspective and in use;

Fig. 2 is a back view;

Fig. 3 is a longitudinal sectional view on the line 3-3 of Fig. 4;

Fig. 4 is a back view of the garment with a portion of the skirt broken away; and

Fig. 5 is a back view of a modified form of construction.

Referring to the drawing, the garment is illustrated as comprising a skirt 10 and trunks 11, the trunks being attached to the skirt portion along the front of the waistline by suitable stitching 12 and, if desired, to the top rear part of the skirt portion by a short strap 12' which may be of elastic material. The suit also includes a top which may conveniently consist of an integral portion 13 of the skirt which extends upwardly from the front and terminates in a point at 14, and a pair of pieces 15 attached to the converging edges of the top, each of these pieces being provided with an extension 16 to pass over the shoulder and a side extension 17 passing beneath the arm. There is no back portion to the top of the garment and the back of the wearer is thus fully exposed except for certain straps.

In the garment illustrated in Fig. 2, each shoulder extension 16 is connected to the side extension 17 on the same side of the garment by a connecting strap 18, the two extensions and the strap defining an enlarged armhole. There are also two straps 19 connected to the top of the trunks at the rear on opposite sides of the middle of the waistline and extending upward therefrom and the straps 19 are to be passed beneath the connecting straps 18 and tied together. When the tying straps are passed through the armholes and the free ends of the tying straps brought together at the middle of the back and tied, the pull of the tying straps draws the connecting straps 18 toward each other across the back of the garment and this causes the front of the garment to be wrapped closely about the body of the wearer, the tying straps being sufficiently long to permit a considerable variation in the tightness of the fit.

In the construction illustrated in Figure 5, the connecting straps 18 connect a shoulder extension 16 at one side of the garment to the side extension 17 at the opposite side, and in this style of garment also, each tying strap

19 is passed beneath a connecting strap and the ends of the tying straps brought together. The connecting straps of this garment are sufficiently loose to permit the garment to be readily put on and taken off, and if the tying straps were not provided, the point of crossing of the connecting straps would tend to lie high up the back. This would make the front of the garment fit the wearer loosely and the suit would have an unattractive appearance.

In both forms of the garment, it will be observed that the top edge 20 at the rear of the trunks lies slightly below the top edge 21 of the skirt, and the pieces 15 are preferably formed with darts or pleats 22 to cause these pieces to fit the figure closely. Instead of forming the top of the garment of the pointed upward extension from the skirt and the two pieces 15, it will be understood that the top may be a single piece extending upward from the front of the waistline. The construction illustrated is preferred, however, because it gives the garment a neater appearance and better fit.

In the construction illustrated in Figure 2, the straps 18 connecting the extensions 16 and 17 are untwisted, while in the form illustrated in Figure 3, each of these straps is given a twist. With the latter arrangement, the tying strap makes a smooth contact with the connecting strap at the middle of the twist.

What I claim is:

1. A bathing suit which comprises trunks, a skirt, a front portion above the skirt having spaced extensions at the top thereof and side extensions beneath the arms, a pair of straps each connecting one of said spaced extensions to a side extension and with said extension providing armholes, and a pair of straps attached to the top rear part of the trunks and sufficiently long to be passed each beneath one of the connecting straps and have their free ends tied together.

2. A bathing suit which comprises trunks, a skirt, a front portion above the skirt having spaced extensions at its top and side extensions beneath the arms, a pair of straps each connecting one of said spaced extensions to the side extension at the other side of the garment, and a pair of straps attached to the top rear part of the trunks and sufficiently long to be passed each beneath one of the connecting straps and to have their free ends tied together.

3. A bathing suit which comprises a skirt, trunks within the skirt and connected thereto along the front part of the waistline, and a front above the skirt having spaced extensions at its top and side extensions beneath the arms, a pair of straps each connecting one of said spaced extensions to a side extension and with said extensions providing armholes, and a pair of straps attached to the

top rear part of the trunks and sufficiently long to be passed each beneath one of the connecting straps and to have their free ends tied together.

4. A bathing suit which comprises trunks, a skirt having a portion at the front extending above the waistline and terminating substantially in a point lying above the middle of the waistline in front, a pair of top members each attached to the top portion of the skirt along the converging edges thereof, each member having a top extension and a side extension beneath an arm, connecting straps attached each to one end of a top extension and to one end of a side extension, and a pair of straps attached to the top rear part of the trunks at opposite sides of the middle thereof, said straps being sufficiently long to be passed each beneath one of the connecting straps and to have their free ends brought toward each other and tied together.

5. A bathing suit which comprises trunks, a skirt having a portion at the front extending above the waistline and terminating substantially in a point lying above the middle of the waistline in front, a pair of top members each attached to the top portion of the skirt along the converging edges thereof, each member having a top extension and a side extension beneath an arm, connecting straps attached each to one end of a top extension and to one end of a side extension, said straps being crossed at the back of the garment, and a pair of straps attached to the top rear part of the trunks at opposite sides of the middle thereof, said straps being sufficiently long to be passed each beneath one of the connecting straps and to have their free ends brought toward each other and tied together.

6. A bathing suit comprising a body portion having armholes defined in part by shoulder straps, a trunk member lying within the body portion and attached thereto at the front only and free at the rear, and means attached to said trunk member and passing through said armholes and extending circumferentially from one armhole to the other for drawing said body portion snug around the body of the wearer.

7. A bathing suit comprising a body portion having armholes defined in part by shoulder straps, a trunk member lying within the body portion and attached thereto at the front only and free at the rear, and straps attached to said trunk member and passing through said armholes and connected together between the armholes for drawing said body portion snug around the body of the wearer.

8. A bathing suit comprising a body portion having armholes defined in part by shoulder straps, a trunk member lying within the body portion and secured to the body

portion at the front by stitching and at the rear by a strap, and straps attached to said trunk member and passing through said armholes and connected together between the 5 armholes for drawing said body portion snug around the body of the wearer.

In testimony whereof I affix my signature.
LILI JUST.
